UNITED STATES PATENT OFFICE

2,688,501

EXHAUST MANIFOLD JOINT

Merlin W. MacLeod, Winnipeg, Manitoba, Canada, assignor to Trans-Canada Air Lines, Montreal, Quebec, Canada, a corporation of Canada

Application August 21, 1950, Serial No. 180,546

1. Claim. (Cl. 285—162)

1. The invention relates to new and useful improvements in exhaust systems and particularly to exhaust systems for aero-engines of the multi-bank, in-line type, an object of the invention being to provide a device of the character herewithin described whereby the exhaust gases from the bank of cylinders adjacent the fuselage of the aircraft are transferred to the opposite side of the engine remote from the fuselage and then connected into an exhaust tail-pipe.

A further object of the invention in conjunction with the foregoing object is to provide a device of the character herewithin described, the use of which reduces considerably the volume of exhaust noise heard in the cabin of the aircraft.

Another object of the invention is to provide a device of the character herewithin described in which the component parts are readily interchangeable from a port to starboard engine thereby simplifying manufacturing and maintenance problems.

A still further object of the invention is to provide an exhaust system of the character herewithin described which interferes as little as practicable with the exhaust gas flow from the cylinders to atmosphere, by which is meant that the back pressure of the exhaust gases will be increased as little as practicable.

Another object of the invention is to provide a device of the character herewithin described which includes a novel expansion joint thereby permitting linear expansion and contraction of the exhaust manifold in relation to the individual exhaust stub pipes, a serious problem in in-line engine exhaust collecting systems.

A still further object of the device in conjunction with the foregoing object is to provide an expansion joint of the character herewithin described which is extremely simple in manufacture and efficient in operation.

A further object of the invention is to provide an expansion joint of the character herewithin described which is adapted to be fitted relatively close to the exhaust port thereby enabling the expulsion of exhaust gases to provide an aspirating effect instead of a positive pressure effect thereby eliminating the necessity of a rigid, clamped joint.

A yet further object of the invention is to provide a device of the character herewithin described in which the aforementioned expansion joints are permitted to expand and contract in the plane of the joints independently of one another, thereby taking into consideration differences of temperature existing at each exhaust port.

2.

A still further object of the invention is to provide a device of the character herewithin described in which the expansion joints hereinbefore mentioned are so constructed as to allow an annular air-cooling heat dissipating area within the slip-seating thereof.

Another object of the invention is to provide a device of the character herewithin described in which the saddle duct does not interfere with the efficient streamlining of the engine as said duct can be of streamlined section itself and can be retained sufficiently close to the periphery of the engine that it can follow the external transverse contour of the engine at the point at which it spans same.

Another object of the invention is to provide a device of the character herewithin described which is particularly well adapted for efficient air-cooling by relatively simple ducting arrangements.

A yet further object of the invention in conjunction with the foregoing object is to provide a system of the character herewithin described in which efficient air-cooling is possible over the entire exhaust system thereby eliminating hot spots and the like.

Yet another object of the invention is to provide an exhaust system of the character herewithin described which is relatively economical in manufacture, simple in construction, easy to maintain, and otherwise well suited for the purpose for which it is designed.

With the foregoing objects in view, and such other objects and advantages as will become apparent to those skilled in the art to which this invention relates as this specification proceeds, the invention consists essentially in the arrangement and construction of parts all as hereinafter more particularly described, reference being had to the accompanying drawings in which:

Figure 1 is a top plan view of the exhaust system installed upon a twin-bank in-line engine.

Figure 2 is a front end view of Figure 1.

Figure 3 is a side elevational view of one side of the exhaust system.

Figure 4 is an enlarged side elevation of one of the expansion joints.

Figure 5 is a vertical section of Figure 4.

In the drawings like characters of reference indicate corresponding parts in the different figures.

The present invention relates to an exhaust system whereby the exhaust gases of the bank of cylinders adjacent the fuselage of the aircraft are conducted over the engine and remote from the fuselage thereby relieving the exhaust

noise heard within the cabin considerably. By ducting the exhaust gases over the engine, the engine nacelle acts as a shield being interposed between the exhaust tail-pipe and the fuselage, as well as removing the point of egress of the gases a considerable distance away from the fuselage.

In conjunction with the normal exhaust system hereinafter to be described, a novel expansion joint is disclosed, as it is essential, in a system of this nature, to provide means for longitudinal expansion and contraction of the manifold in relation to the individual exhaust ports of an in-line engine to which it is connected.

Reference to the accompanying drawings will show that an in-line engine of the V-bank type is illustrated schematically and indicated generally by the reference character 1. It represents an engine situated upon the port or left-hand side of the aircraft (not shown) and includes two banks of in-line cylinders 2 and 3. Exhaust stub pipes 4 are bolted to the exhaust ports 5' of the individual cylinders and communicate with exhaust manifolds 5 and 6. These manifolds are substantially in line with the longitudinal axis 7 of the engine and are connected together by a duct or saddle 8 overspanning the engine substantially towards the rear end 9 thereof as shown most clearly in Figure 1.

In detail, each of the manifolds 5 and 6 includes a longitudinally extending portion 10 substantially circular in cross-section and increasing in area from the forward end 11 thereof towards the rear end 12 thereof for the purpose hereinafter to be described.

Exhaust stub pipes 4 extend from the exhaust port 5' of each of the in-line cylinders and communicate with the portion 10 of the manifolds through the medium of an expansion joint collectively designated 13.

The manifolds 5 and 6 are supported by means of brackets 14 extending between the extremities thereof and an adjacent point of support 15 upon the cylinder banks 2 and 3. Brackets 14 include a pair of plates 16 bolted at one end thereof to clevises 17 which in turn are bolted to attachment plates 18 welded to the manifolds. The opposite ends of plates 16 are bolted to an angulated bracket 19 which in turn is bolted to the aforementioned points of attachment 15.

By this means the manifolds are held suspended upon brackets 14 and are capable of a certain amount of movement longitudinally due to the effects of expansion and contraction caused by the exhaust gases passing therethrough.

The rear ends 12 of the manifolds open internally into a T-branch 20, the axis of this branch being substantially at right angles to the longitudinal axis of the portion 10 of the manifolds. The inner ends 21 of the T-branches 20 are connected by the aforementioned duct or saddle 8 which is retained in position by means of clamp assemblies 22 which, in turn, are supported by brackets 23 secured to the engine block. The saddle 8 overspans the engine block substantially towards the rear thereof and is curved semi-circularly to present a circumferential flow to exhaust gases passing therethrough, the aforementioned T-branches 20 of the manifolds being curved also as clearly indicated in Figure 2 of the accompanying drawings. This curvature is necessary because of the angle between the two banks of cylinders 2 and 3 and because of the necessity to prevent a rapid change of direction of the gas flow.

The cross-sectional configuration of the saddle 8 as well as the T-branches 20 of the manifolds, are substantially elliptical or ovoid in order to present a minimum area 24 to the air flow and in order to fair-in with the frontal configuration of the engine and the like.

The outer ends 25 of the T-branches of the manifolds are downwardly turned when viewed from the front of the engine, the end of manifold 10 5 being provided with a blanking plug 26 insertable therein and secured by bolts 27. The end 25 of manifold 6 is connected to an exhaust tail-pipe section 28 which extends downwardly and rearwardly to a point adjacent the trailing edge of the 15 wing of the aircraft (not illustrated).

From the foregoing it will be appreciated that the exhaust gases passing through the exhaust stub pipes 4, enter the manifolds 5 and 6, and in this connection, it will be appreciated that the 20 cross-sectional area of the manifold increases in order to accommodate the gases from each additional cylinder connected thereto. The gases are then ducted from the bank of cylinders 2, over the engine block, and join the exhaust gases from the 25 bank of cylinders 3 which are discharging into the manifold 6. The exhaust gases of both banks then pass downwardly and outwardly to the tail-pipe 28 which is situated on the side of the engine remote from the fuselage of the aircraft.

30 As hereinbefore described, the engine shown is assumed to be situated upon the port side of the aircraft but, the starboard system would be similar with the exception that the aforementioned blanking plug 26 would be fitted upon the opposite 35 manifold, and the exhaust tail-pipe section 28 reversed to the other side.

Due to the configuration and lay-out of the manifolds 5 and 6, it will be appreciated that considerable longitudinal expansion and contraction 40 movement will take place between said manifold and the exhaust ports connected thereto.

Consequently, it is necessary to provide means to permit this expansion and contraction and the expansion joint collectively designated 13 has 45 been found extremely satisfactory in this respect.

Reference to Figures 4 and 5 will show the detailed structure of these expansion joints and it will be seen that they consist of what is defined as an annular and planar slip-seating collectively 50 designated 29 and an annular floating flange designated 30 positioned therein.

The slip-seating 29 comprises an outturned annular flange 31 which is provided on the exhaust manifold and is disposed in a plane perpendicular 55 to the axis of the joint. A marginal rim 33 is provided at the periphery 34 of the flange 31 and a complementary annulus 32 has its outer edge secured by welding, or the like, to the rim 33. The annulus 32 is juxtaposed in spaced relation to the flange 31 and coacts with the flange and with the rim 33 to provide an annular seat 37 which is open at its inner side and is disposed in a plane 60 perpendicular to the axis of the joint.

65 A rigid annular adapter 40 is provided on the exhaust stub pipe 4 and extends into the annulus 32. The adapter 40 is equipped with an outturned annular flange 39 which is freely and slidably disposed in the seat 37 through the open inner side 70 of the latter. It is to be noted that the periphery of the flange 39 is spaced inwardly from the rim 33 as shown at 42, while the inner edge of the annulus 32 is spaced outwardly from the adapter 40. By virtue of this arrangement the flange 39 75 may not only expand radially in the seat 37, but

may also slide laterally in the plane of the seat with respect to the flange 31.

Thus, the expansion joint is self-adjusting in response to both expansion and lateral movement or axial misalignment, which feature is of considerable importance where several such joints are used in a row on an exhaust manifold and the latter, responding to a rise in temperature, expands longitudinally so that the distance between the axes of the manifold branches leading to the individual cylinder stub pipes is subject to substantial variations. Under such conditions, a joint constructed in accordance with the invention will automatically adjust itself to such variations without any binding, locking or deformation.

It will be also noted that the joint permits heat dissipation to take place, together with the over-all configuration of the joint which in fact acts as a cooling fin for this particular section of the exhaust system. Furthermore, due to the 20 closeness of this expansion joint to the exhaust ports of the engine, exhaust gases passing therethrough have sufficient velocity to cause aspiration rather than blowing at this point thereby eliminating the necessity for rigid, clamped joints 25 which would prevent expansion and contraction from taking place.

In conclusion, it is desired to stress that an exhaust system of this nature, particularly adapted for in-line engines, necessitates the use 30 of an expansion joint adjacent each exhaust port in order to permit contraction and expansion to take place along the points of connection to the manifold. Furthermore, in an exhaust system of the character hereinbefore described efficient air-cooling thereof may readily be undertaken by cowlings as shown in Figure 3 and indicated by the reference character 45, by which means air-flow may be routed as indicated by arrows 46 without interference with the rest of the operation of the engine.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many ap- 50

parently widely different embodiments of this invention may be made within the spirit and scope of the accompanying claim without departing from such spirit and scope, it is intended that all matter contained in the accompanying specification shall be interpreted as illustrative only and not in a limiting sense and I desire only such limitations placed thereon as justice dictates.

What I claim as my invention is:

In combination with first and second conduits subjected to relative lateral movement and expansion, a self-adjusting joint comprising an outturned annular flange provided on the first conduit and disposed in a plane perpendicular to the axis thereof, a marginal rim provided at the periphery of said flange, a complementary annulus secured at its outer edge to said rim and juxtaposed in spaced relation to said flange, said flange coacting with said annulus and said rim to provide an annular seat open at its inner side and disposed in a plane perpendicular to the axis of said first conduit, a rigid annular adapter provided on the second conduit and extending into said annulus, and an outturned annular flange provided on said adapter and disposed slidably in said seat through the open inner side of the latter, the periphery of said last mentioned flange being spaced inwardly from said rim and the inner edge of said annulus being spaced outwardly from said adapter, whereby said last mentioned flange may expand radially in said seat and slide laterally in the plane of the seat with respect to the first mentioned flange.
